ELECTRIC TRACK FOR TOY VEHICLES

Ernst Horn, Nuremberg, Germany

Application September 8, 1936, Serial No. 99,820
In Germany February 7, 1936

1 Claim. (Cl. 104—149)

This invention relates to track-bodies for toy-vehicles, such as toy-automobiles or other vehicles travelling on a track without rails, and more particularly to a double track-body comprising two individual tracks placed side by side, and consists essentially of a double track-body equipped for electric service, in such a manner that both of said individual tracks are conductively connected with each other to form the ground for the electrical supply system, each individual track being for this purpose provided with a special current supply rail and an electrical circuit that may be independently regulated to permit toy-vehicles to travel on either of said individual tracks with different and variable velocities.

A further feature of my invention is that said double track-body is provided, besides the two individual or main tracks, with one or more side tracks controlled by switches inserted at the point of junction between said main and said side-track or tracks, the latter forming a connection between the one and the other of said main tracks and including an insulator for the operating current permitting the toy-vehicles travelling on the one of said main tracks to be switched over to said second main track.

In my invention there is provided a novel track-body for toy-vehicles travelling on a track without rails, said track-body being equipped for electrical operation and offering the possibility of running two toy-vehicles in the same or in opposite direction on either of said main tracks with any desired and regulable velocity.

Since both electrical circuits for operating the two tracks and the toy-vehicle travelling thereon are regulable independently of each other, it will also be possible to run a single toy-vehicle on any of the main or side-tracks.

In the accompanying drawings I have represented an example of a construction of my novel track-body, Fig. 1 being a top-view of the assembled track-body with the main and side-tracks, Fig. 2 showing in an enlarged scale the current supply member supplying operating current to all of said tracks and to the toy-vehicles travelling thereon, while Fig. 3 is a cross-section taken on Fig. 2. Fig. 4 is a further enlarged top-view of a member of the track-body including a track-switch provided at the point of junction between a main and a side-track, while Fig. 5 is a bottom-view taken on Fig. 4, and Fig. 6 a transverse section through track-body showing the two main tracks with two toy-vehicles, such as toy-automobiles, running thereon.

Referring more particularly to the drawings,

the track-body as a whole is composed of several track-members which when assembled will present a ring-shaped double track comprising two individual closed tracks placed side by side.

The two main tracks 1 are made by properly shaped depressions in each track-member with a central elevated wall between said two tracks, as may be seen from Fig. 6. Into the track-body there is inserted at certain places thereof a track-member including a switch 2 consisting essentially of a swingable tongue 4 permitting in one position thereof a pair of connections between a main track and one or more side-tracks 1', the latter making connection between said two main tracks so that a toy-vehicle may be run from one into the other main track.

The side-tracks 1' may be passed underneath the main tracks at those points where the side tracks cross the main tracks. It will, however, also be possible to pass said side-tracks in the form of bridges above said main tracks if desired.

According to this invention the track-body is further provided within either main and side-track with a central insulated rail 10 which may be supplied with electric current, for instance, from the track-member 7 of the track-body. The track-member 7 is provided with a bridge 8 connecting all of the main and side-tracks conductively to a ground, that is, to the track-body. A second conducting bridge 9 is mounted on said track-member 7 and insulated from the track-body carrying separate current conduits leading to the current rail 10 within each track. The bridge 8 accordingly is equipped with one terminal in conductive connection with the track-body 1' and the bridge 9 is equipped with two terminals, each connected to one of the rails 10, whereby two operating circuits are formed of which each may be controlled by a special step-switch, permitting regulation of either circuit in such a manner that relatively small regulable voltages may be impressed onto either circuit, said voltages varying from between 14 and 20 volts.

The said two step-switches may also be united with a transformer 11 which is necessary for the electrical operation of the toy-vehicles on the track-body, as may be seen from Fig. 1. According to Fig. 1, as shown at the lower left-hand part thereof, the secondary coil of transformer 11 is provided with contact-carriers 12 having insulated contacts tapping said secondary coil, which contacts may alternately be inserted into the secondary circuit by means of a contact-slide, contact-lever 14 or the like to connect said coil with one of the tracks 1. The contacts of the left- 55

hand slide or lever 14' are connected by leads 13 to the right hand taps of the secondary coil, of the transformer 11 and connect the same to the other track 1. Thus a current of one intensity may be supplied to one track 1 while a current of different intensity is simultaneously supplied to the other.

Inserted into the side-tracks 1' leading from the one into the other main track 1' is an insulator 5, 10 by which the circuits having different voltages for the two main tracks do not come in contact with each other, thus permitting independent control of the two track voltages.

The current supply rails 10 are interrupted at 15 the switches 2, said rails 10 being, however, conductively connected by means of an under bridge-plate b. The tongue 4 mounted on the center piece of the switch, may be swung around the pivot 4' and may, for instance, be adjusted by 20 electro-magnetic means. For this purpose an armature 3' which co-operates with an electro-magnet 3 serves to actuate said tongue, which by means of a spring is normally kept in a closed position to keep the main track open for passage 25 of a toy-vehicle. If by means of a contact making device a current impulse is passed through the magnet-coil 3, the latter will attract the armature 3' with the result that the tongue of the switch is swung into the position shown in Fig. 4 30 in dotted lines, the main track being thus blocked and the side-track opened to permit entrance of a toy-vehicle into the latter. The tongue forming part of this switch will of course move above the current supply rails 10 and, therefore, not 35 come into contact with said rails. Figs. 4 and 5 show especially the insulated carrier for the current supply rails, said carrier including plates 20 and 21 of insulating material mounted respectively on the top and underside of the profile of 40 the double-track-body.

The toy-vehicles travelling on the several tracks may be of the form of toy-automobiles or the like as shown in Fig. 6.

The toy-vehicles may be provided with an under current receiving member S sliding on the current supply rail 10, whereby current is supplied to a motor (not shown) provided in the toy-vehicle, said motor causing the travel of the latter within the respective track.

I claim:

In a railless track for toy vehicles, including a plurality of sections each being formed from a single piece of metal, each section being formed to provide a pair of separate and parallel trough-shaped track portions, said sections being joined together end to end to form a continuous course comprising two continuous and concentric track portions, and an electric current carrying rail 10 carried centrally of each track portion; at least one shunt track comprising a separate trough-shaped track portion connecting one of said concentric track portions with the other, said shunt track having a current carrying rail 15 operatively connected to the current carrying rails of said concentric track portions, said shunt track being arranged to transfer a vehicle from one track portion to another in a manner to reverse the direction of travel of said vehicle on said second track portion, a single source of electric current, a single transformer connected to said source of current, a single connection from one pole of said transformer to one section of said metal track to provide a ground for both track portions and 20 said shunt, a separate connection from the other pole of said transformer to each current carrying rail of said portions, and separate means interposed in each of said last named connections for independently regulating the voltage of the current supplied to each current carrying rail of said concentric track portions, and means on 25 said shunt for preventing the current supplied to the current carrying rail of one concentric track portion from reaching the current carrying rail of the other.

ERNST HORN.
